UNITED STATES PATENT OFFICE.

NELSON LEWIS, OF BOULDER, COLORADO.

FLY-SCREEN.

1,077,247.

Specification of Letters Patent.

Patented Oct. 28, 1913.

Application filed November 12, 1910. Serial No. 592,007.

To all whom it may concern:

Be it known that I, NELSON LEWIS, a citizen of the United States, residing at Boulder, in the county of Boulder and State of Colorado, have invented new and useful Improvements in Fly-Screens, of which the following is a specification.

This invention relates to window and door screens used for the exclusion of flies and other insects.

The primary object of the invention is to take advantage of the well known aptitude of such insects when lying upon a vertical surface to crawl upward and to provide for an exit from, but no entrance to the room.

Another object of the invention is to provide a frame for a door or window having one or more panels formed of reticulated material, the same being inclined from the bottom of the door or window frame toward the upper portion thereof, and when more than one of said panels are employed a space is formed between the same, the said space not only providing for the escape of air, so as to thoroughly ventilate the room in which the screen is positioned, but also serving as a means for directing the insect upwardly upon the panel to the exit thereof.

A still further object of the invention is to provide a window or door screen having a plurality of reticulated panels, the lower panel being positioned within an angular cut provided in the stiles of either the door or window frame, the said panel having its upper ends secured to the transversely arranged bar, the succeeding panel having its edges also secured within angular recesses provided within the stiles and having its lower extremity formed with a substantially U-shaped pocket, the latter being connected with a bar or strip positioned directly opposite the bar or strip connecting the upper extremity of the first named panel, so that insects may readily crawl between the spaces formed between each panel and the pocket of the adjacent panel, but wherein the said pocket serves as a means for preventing the downward crawling of the insect to reenter the room.

With the above and other objects in view, which will appear as the description progresses, the invention resides in the novel construction and arrangement of parts hereinafter fully described and claimed.

In the accompanying drawing:—Figure 1 is a perspective view of a door frame pro-

vided with the improved screen: Fig. 2 is a central vertical sectional view taken on a line with one of the outlets formed in the upper bar of the frame. Fig. 3 is a similar sectional view taken on the line 3—3 of Fig. 1.

In the accompanying drawings the device has been illustrated as applied to the frame of a screen door, but it is to be understood that the showing therein is merely illustrative and I do not limit the application of the peculiar arrangement of screen panels to any particular structure, as the said panels could be used with equal efficiency upon a window screen frame, door or window openings or the like.

In the accompanying drawings the numeral 1 designates an ordinary screen door frame. This frame 1 has its vertical stiles provided with inclined grooves or recesses 2. The grooves or recesses 2 may be of any desired number and the said grooves are adapted for the reception of panels formed of reticulated material, such as a wire meshing 3. The door frame is provided with a plurality of oppositely disposed transversely arranged bars 4, the latter connecting the vertical stiles of the frame and being adapted to serve as hand holds whereby the door may be swung upon its hinges as well as for an additional purpose, which is now to be described.

The first groove or recess 2 starts from the lower inner face of the frame 1 and terminates approximately central of the outer bar 4 as clearly illustrated in the figures of the drawings. When the first panel making up the screen is positioned within the oppositely disposed recesses 2, the edges thereof are secured upon the vertical stiles through the medium of brads or nails 5. The second or succeeding recess 2 is started upon the inner face of the door directly opposite the terminal of the first panel. This groove or recess is extended toward and terminates approximately central of the second bar 4 upon the outer face of the frame 1. The reticulated panel 3 is positioned within the said grooves or recesses and retained through the medium of the elements 5. The lower extremity of the said screen is bent longitudinally to provide the cross-sectional U-shaped pockets 6. These pockets 6 terminate a suitable distance away from the upper end of the lower panel 2, so that an insect may find an exit between the pocket and the panel. The inner bar 4 is

positioned a slight distance below the top of the outer bar and the pocket 6 is secured thereto through the medium of suitable springs or other attaching devices.

5 The panels making up the screen are each constructed in a manner similar to that above described and are also connected with the side stiles of the door by having their edges inserted within the grooves or recesses and 10 retained therein by brads, nails or the like. The upper connecting bar 7 of the door is formed with a pair of recesses or depressions 8. Each of these recesses are preferably arranged centrally of the connecting bar 7 and 15 extend longitudinally a suitable distance beyond their points of connection of the said bar with the stiles of the door. The recesses have their side walls parallel and their faces arranged in an inclination similar to the inclined panels 3. The upper screen section 20 or panel, which is adapted to be retained by the upper outer bar 4 is arranged directly opposite the top of the cross sectional U-shaped pocket 9 formed in the panels 10 which engage the inclined depressions 8.

With a screen constructed as above described, the insects upon the interior of a room may crawl upwardly between the panels to find a free exit through the passage 30 formed between the rounded pockets 6 and the top of the next lowest screen. Most all insects have an aptitude for seeking light and fresh air and very few insects are known to crawl downwardly toward a darkened 35 surface. The space between the screen panels affords a lighted surface as well as an exit

of impure air from the room and the said air will serve as a means for forcing the insects upon any of the panels through the exit. The pockets 6 are adapted to serve as 40 retarding elements for such insects as fall upon the screens or attempt to descend downwardly to gain an entrance into the room upon which the door is positioned.

Having thus described the invention, what 45 I claim is,

A screen comprising a frame having vertical stiles, bars attached to the stiles against the inner and outer surfaces thereof and arranged in pairs, the outer members of the 50 pairs of bars being located at higher points along the stiles than the inner members of the pairs of bars, screen panels having their upper edges connected with the inner surfaces of the upper and outer bars and their lower portions connected with the inner surfaces of the next adjacent inner lower bars, the intermediate portions of the panels lying in planes which extend transversely across the stiles from the inner to the outer surfaces thereof and which extend from one set of bars to the next adjacent set of bars, the lower portions of the panels being curved 60 inwardly forming pockets located between the inner surfaces of the members of the 65 pairs of bars.

In testimony whereof I affix my signature in presence of two witnesses.

NELSON LEWIS.
